UNITED STATES PATENT OFFICE.

FREDERIC G. NICOLAUS, OF CLEVELAND, OHIO.

RECEPTACLE-CLOSER.

SPECIFICATION forming part of Letters Patent No. 788,553, dated May 2, 1905.

Application filed January 21, 1905. Serial No. 242,179.

To all whom it may concern:

Be it known that I, FREDERIC G. NICOLAUS, a citizen of the United States of America, residing at Cleveland, in the county of Cuyahoga and State of Ohio, have invented certain new and useful Improvements in Receptacle-Closers; and I hereby declare the following to be a full, clear, and exact description of the invention, such as will enable others skilled in the art to which it pertains to make and use the same.

This invention relates to improvements in receptacle-closers more especially designed for use in connection with pouches or bags.

15 The primary object of this invention is to provide a receptacle-closer which is more especially suitable for use in forming a valved inlet and outlet for a tobacco-pouch to be carried in pocket, which is readily applied to and detached from any pouch, which does not objectionably enlarge the pouch, and which is simple and inexpensive in construction.

20 With this object in view this invention consists in certain features of construction and 25 combinations of parts hereinafter described, and pointed out in the claims.

25 In the accompanying drawings, Figures 1 and 2 are top plans of a receptacle-closer embodying my invention. In Fig. 1 the two co- 30 operating cut-offs or valves of the receptacle-closer are shown closed, whereas in Fig. 2 they are shown open. Fig. 3 is a side elevation relative to Fig. 1. Fig. 4 is a top plan in section on line 4-4, Fig. 3. Fig. 5 is a bottom plan of the cap of the receptacle-closer. 35 Fig. 6 is a section on line 6-6, Fig. 1, looking in the direction indicated by the arrow.

40 My improved receptacle-closer comprises, preferably, a neck-forming sheet-metal ring or tubular member A, which is adapted to be inserted within a hole or aperture with which the bag, pouch, or receptacle (not shown) which is to be provided with my improved receptacle-closer is to be provided. The 45 neck A is adapted to be secured to the bag, pouch, or receptacle in any approved manner. The neck A in the device illustrated is provided at its lower or inner end and externally with an annular flange 10. The neck A is

provided at its upper or outer end and externally with an annular flange 12, which is considerably wider than the flange 10, and provided with two upwardly or outwardly projecting pivot-forming lugs 13, which are arranged at diametrically opposite sides, respectively, of the passage-way formed largely within and extending through the neck A, as at α , and partially by an opening or hole b , formed in and centrally of a sheet-metal cap B, arranged at the outer side of the flange 12 50 and far enough from the said flange to accommodate the location and operation between the cap and the said flange of two co-operating corresponding cut-offs or valves D, which consist each of a horizontally-arranged 55 sheet-metal plate resting upon and having bearing against the outer side of the flange 12 and provided with a circular hole d . The hole d in one of the valves D is engaged by one of the lugs 13, and the hole d of the other 60 valve is engaged by the other lug 13. It will be observed, therefore, that the engagement of a lug 13 with the hole d of a valve D forms the pivotal connection between the said valve and the flange 12 of the neck A. 75

The valves D have the arrangement and dimensions required to render them capable of completely closing the passage-way extending through the neck A or to avoid interruption of the continuity in the said passage-way, according as they are in their closed or open position. 80

In Figs. 1, 3, 4, and 6 the valves D are shown in their closed position. In Fig. 2 the valves D are shown open. 85

Preferably the opposing edges of the two valves D have a sinuous trend, and preferably each valve projects, as at 15, a suitable distance from the axis of the valve into the other valve, which is correspondingly recessed, as 90 at 16, between its projecting portion 15 and its axis, and the projecting portion 15 of each valve engages the recess 16 in the other valve in the closed position of the valves. It will be observed, therefore, that the passage-way 95 through the receptacle-closer is not materially interfered with by the valves D when the latter are open.

The cap B, as already indicated, affords a bearing for the outer side and prevents upward or outward displacement of the valves D and rests upon and is soldered or otherwise secured to lugs 14, which are formed upon the outer side of the flange 12. The lugs 14 are arranged as required to accommodate the location and operation of the valves D.

The cap B (see Figs. 5 and 6) is an annular sheet-metal stamping bent to form two inwardly-projecting annular flanges 17 and 18 at the inner side of the cap, which flanges extend around the hole b in the cap and are spaced apart to form an annular recess 20 between the said flanges, which recess accommodates the location and operation of a bow-spring G, which acts to retain the valves D in their closed position. Preferably the cap is soldered at its outer flange 18 to the flange 12 and has its inner flange 17 arranged to extend across the projecting portions 15 of the valves D in both positions of the valves.

Each valve D is provided near the axis of the valve with a laterally and outwardly projecting arm 22, which extends laterally beyond the outer side of the circumferential edge of the flange 12 of the neck A and is provided at its outer end with a pressure-receiving lip 23, arranged to engage the outer surface of the cap B in the open position of the valves, and consequently limiting the movement of the valve in actuating the valve from its closed into its open position. The arms 22 are so arranged relative to the axes of the valves that pressure exerted inwardly simultaneously upon the outer sides of the lip 23 of the said arms results in the simultaneous actuation of the said valves into an open position against the action of the spring G, which is arranged within and extends along the recess 20 and is operatively connected with the arms 22 of both valves. The arms 22 are arranged at opposite sides, respectively, of an imaginary straight line intersecting the axes of the valves, and preferably opposite ends of the spring G embrace or are attached to a lug 24, formed upon the different arms 22, respectively.

My improved receptacle-closer in applying it to a tobacco-pouch is inserted within the open end of the pouch, whereupon the pouch is tied to and around the neck A between the flanges 10 and 12.

What I claim is—

1. A receptacle-closer having a passage-way extending therethrough and comprising two cut-offs or valves normally closing opposite sides respectively of the said passage-way, which valves are movable from or toward each other according as they are in their closed or open position; bearings for the valves at the inner sides of the valves; means for preventing displacement of the valves outwardly from the said bearings, and a single spring oper-

atively connected with and acting to retain both valves in their closed position.

2. A receptacle-closer having a passage-way extending therethrough and comprising two cut-offs or valves normally closing opposite sides respectively of the said passage-way, which valves are movable from or toward each other according as they are in their closed or open position; bearings for the valves at the inner sides of the valves; means for preventing displacement of the valves outwardly from the said bearings, and means acting to retain the valves in their closed position.

3. A receptacle-closer having a passage-way extending therethrough and comprising two cut-offs or valves normally closing opposite sides respectively of the said passage-way, which valves are movable from or toward each other according as they are in their closed or open position; bearings for the valves at the inner sides of the valves, and means acting to retain the valves in their closed position.

4. A receptacle-closer having a passage-way extending therethrough and comprising two cut-offs or valves normally closing opposite sides respectively of the said passage-way, which valves are movable from or toward each other according as they are in their closed or open position, and a single spring operatively connected with and acting to retain both valves in their closed position.

5. A receptacle-closer having a passage-way extending therethrough and comprising two cut-offs or valves normally closing opposite sides respectively of the said passage-way, which valves are movable from or toward each other according as they are in their closed or open position; bearings for the valves at the inner sides of the valves, and means acting to retain the valves in their closed position, and the outer end of the aforesaid passage-way being formed by an opening formed in a cap which is arranged at the outer sides of the valves.

6. A receptacle-closer having a passage-way extending therethrough and comprising two cut-offs or valves pivoted at and normally closing opposite sides respectively of the passage-way, which valves are arranged to swing from or toward each other according as they are in their closed or open position, and means acting to retain the valves in their closed position.

7. A receptacle-closer having a passage-way extending therethrough and comprising two valve-forming plates pivoted at and normally closing opposite sides respectively of the passage-way, which plates are arranged to swing from or toward each other according as they are in their closed or open position, and the opposing edges of the plates having a sinuous trend.

8. A receptacle-closer comprising a tubular member instrumental in forming a passage-

way and provided with two cut-offs or valves normally closing opposite sides respectively of the aforesaid passage-way, which valves are movable from or toward each other according as they are in their closed or open position; a cap arranged at the outer sides of the valves and having a centrally-located hole or opening forming the outer portion of the aforesaid passage-way, and means acting to retain the valves in their closed position.

9. A receptacle-closer comprising a tubular member instrumental in forming a passage-way and provided, at its outer end and externally, with an annular flange; two cut-offs or valves arranged at the outer side of the said flange and normally closing opposite sides respectively of the aforesaid passage-way, which valves are movable from or toward each other according as they are in their closed or open position; a cap arranged at the outer sides of the valves and having a centrally-located hole or opening forming the outer portion of the aforesaid passage-way, and means acting to retain the valves in their closed position.

25 10. A receptacle-closer comprising a tubular member having a passage-way extending therethrough and provided, at its outer end and externally, with an annular flange; two cut-offs or valves arranged at the outer side of 30 and pivoted to the flange and normally closing opposite sides respectively of the aforesaid passage-way, which valves are arranged to swing from or toward each other according as they are in their closed or open position, and 35 means acting to retain the valves in their closed position.

11. A receptacle-closer comprising a tubular member having a passage-way extending therethrough and provided, at its outer end 40 and externally, with an annular flange; two cut-offs or valves pivoted to the flange and normally closing opposite sides respectively of the aforesaid passage-way, which valves are arranged to swing from or toward each 45 other according as they are in their closed or open position, and means acting to retain the valves in their closed position.

12. A receptacle-closer comprising a tubular member instrumental in forming a passage-way; two cut-offs or valves normally closing opposite sides respectively of the aforesaid passage-way, which valves are pivotally connected to the aforesaid tubular member and arranged to swing from or toward each other 50 according as they are in their closed or open position; a cap arranged at the outer sides of the valves and secured to the aforesaid tubular member and having a centrally-located hole or opening forming the outer portion of 55 the aforesaid passage-way, which cap is provided, at its inner side, with a recess, and a spring arranged within the said recess and operatively connected with the valves and acting to retain the valves in their closed position.

13. A receptacle-closer comprising a tubular member instrumental in forming a passage-way; two cut-offs or valves normally closing opposite sides respectively of the aforesaid passage-way, which valves are pivotally connected to the aforesaid tubular member and 60 arranged to swing from or toward each other according as they are in their closed or open position; a cap arranged at the outer sides of the valves and secured to the aforesaid tubular member and having a centrally-located hole 65 or opening forming the outer portion of the aforesaid passage-way, which cap is provided, at its inner side, with an annular recess, and a bow-spring arranged within and extending along the said recess and operatively connected with the valves and acting to retain the valves in their closed position.

14. A receptacle-closer comprising a tubular member instrumental in forming a passage-way; two cut-offs or valves normally closing 85 opposite sides respectively of the aforesaid passage-way, which valves are pivotally connected to the aforesaid tubular member at opposite sides respectively of the passage-way and arranged to swing from or toward each 90 other according as they are in their closed or open position; a cap arranged at the outer sides of the valves and secured to the aforesaid tubular member and having a centrally-located hole or opening forming the outer portion 95 of the aforesaid passage-way, which cap is provided, at its inner side, with an annular recess, and a bow-spring arranged within and extending along the said recess and operatively connected with the valves and acting to 100 retain the valves in their closed position.

15. A receptacle-closer comprising a tubular member instrumental in forming a passage-way; two cut-offs or valves normally closing opposite sides respectively of the aforesaid passage-way, which valves are pivotally connected to the aforesaid tubular member at opposite sides respectively of the passage-way and arranged to swing from or toward each other according as they are in their closed or 105 open position; a cap arranged at the outer sides of the valves and secured to the aforesaid tubular member and having a centrally-located hole or opening forming the outer portion 110 of the aforesaid passage-way; means acting to retain the valves in their closed position, and each valve being provided with a lever-forming arm which projects upwardly beyond the cap and terminates at its outer end in a pressure-receiving lip, and the lever-forming arms of the different valves being arranged at opposite sides respectively of a straight imaginary line intersecting the axes 115 of the valves.

16. A receptacle-closer comprising a tubular member instrumental in forming a passage-way and provided, at its outer end and externally, with an annular flange which is pro-

vided at its outer side with outwardly-projecting lugs; two cut-offs or valves arranged at the outer side of the flange and normally closing opposite sides respectively of the afore-
5 said passage-way, which valves are movable from or toward each other according as they are in their closed or open position; a cap ar-
ranged at the outer sides of the valves and se-
cured to the aforesaid lugs, which cap has a
10 centrally-located hole or opening forming the

outer portion of the aforesaid passage-way,
and means acting to retain the valves in their
closed position.

In testimony whereof I sign the foregoing
specification in the presence of two witnesses. 15

FREDERIC G. NICOLAUS.
